ENGINE AIR INTAKE FILTER MEDIUM HOLDER

John Wilfred Bruderlin, Chiswick, New South Wales,
Australia, assignor to Lynx Engineering (Sales) Pty.
Limited, Croydon, New South Wales, Australia

Filed Mar. 30, 1971, Ser. No. 129,659

Claims priority, application Australia Nov. 4, 1970

Term of patent 14 years

Int. Cl. D12—14; D15—01

U.S. Cl. D55—1 R

FIG. 2

FIG. 3

FIG. 4

FIG. 1 is a top plan view of an engine air intake filter medium holder embodying my new design;

FIG. 2 is a cross sectional view taken on line 2—2 of FIG. 1;

FIG. 3 is a cross sectional view taken on line 3—3 of FIG. 1; and

FIG. 4 is a cross sectional view taken on line 4—4 of FIG. 1.

The appearance of the engine air intake filter medium holder is understood to be continuous throughout the complete article shown.

I claim:

The ornamental design for an engine air intake filter medium holder, as shown and described.
